CLAIM

The ornamental design for a pair of shoes as shown and described.

DESCRIPTION

FIG. 1 is a perspective view of the right foot of a pair of shoes showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top view thereof;

FIG. 7 is bottom view thereof;

FIG. 8 is a perspective view of the left foot of a pair of shoes showing my new design;

FIG. 9 is a rear elevation view thereof;

FIG. 10 is a left side elevation view thereof; and,

FIG. 11 is a right side elevation view thereof.

The dotted lines represent portions of the pair of shoes that form no part of the claimed design.

1 Claim, 7 Drawing Sheets
